AUTOMATIC SPARK TIMER

Filed Nov. 24, 1923

INVENTOR.
Charles L. Stokes

UNITED STATES PATENT OFFICE.

CHARLES LAWRENCE STOKES, OF LOS ANGELES, CALIFORNIA.

AUTOMATIC SPARK TIMER.

Application filed November 24, 1923. Serial No. 676,863.

My invention relates to improvements for advancing, or retarding, the time of applying the ignition spark to a mixture of fuel and air in the cylinder of an internal combustion engine.

The principal object of my invention is to automatically advance and retard the spark, thereby obtaining maximum power and maximum economy for all speeds, or loads, of an 10 internal combustion engine.

A further object of my invention is to automatically control said spark according to the pressure generated by the oil pump of an internal combustion engine.

15 Referring to the drawings in which the same numbers indicate like parts:—

Fig. 1 is a view of the apparatus as applied to a spark distributor.

Fig. 2 is a sectional view along the lines 20 A—A of Fig. 1.

The ignition spark for an internal combustion engine is generally controlled by a timer 1, wherein the spark is diverted to the cylinders of an internal combustion engine 25 through any desired number of cables attached to any desired number of plugs 2 in timer housing 1. The timer 1 may be of any well known make and is driven by suitable mechanism from some part of the engine 30 which it serves in the usual manner, and the advance, or retardation, of the timer 1 is accomplished by means of a lever 3 through the manual control of a rod 4 which is held in a hole 5.

35 Inasmuch as many well known constructions of timers 1 are well known, and many means of actuating them are also well known, it is not deemed necessary to show the specific parts thereof, because such are not 40 herein claimed and my apparatus, which is to be further described, may be easily applied to any well known timer.

A second rod 6 is fastened by one end to the lever 3 through a second hole 7 and the 45 rod 6 is threaded at its other end to be firmly fastened to a rod 8 and held therein by a locknut 9.

The actuation of the lever 3 is caused by the movement of a diaphragm, or "bellows" 50 11 by means of the rod 8 which is securely fastened to a cover 10 soldered to one end of the bellows 11, thereby making 11 fluid tight at one end.

A casing 13 is closed at one end by a cover 55 14 which is pressed therein. The casing 13 is provided with a flange 15 whereby said

casing is held by means of screws 16 to the crankcase 17 of an internal combustion engine, or the casing 13 may be attached to any other suitable portion of said engine. 60

11 is soldered interiorly of the casing 13 and has its open end approximately concentric with the open end of said casing so that there may be a free movement of the rod 8 through said open end of 11. 65

The structure as described leaves an annular space 20 between the walls of the bellows 11 and the casing 13 and to this space 20 a pipe 18 is led from the discharge side of the engine oil pump (not shown), and a pipe 19 70 leads from 20 to the interior of the crankcase 17, or any other desired part of the engine. 75

The operation is as follows:—

The oil pump of an interior combustion engine is generally driven from the engine 75 crankshaft by suitable means to the end that the suction, or oil pressure, developed by the oil pump varies in proportion with the increase, or decrease, of the speed of the engine. If now it be assumed that oil pressure is 80 being applied from the oil pump through 18 to 20, the same pressure for any predetermined speed will cause the rods 8 and 6 to advance the timer 1 a predetermined degree of angularity, because the pressure of the 85 oil in the space 20 will cause a compression of the bellows 11.

When the engine is stopped the bellows 11 will expand to a position where the spark will be at the right position for starting the 90 engine, it being noted that the oil under pressure will pass continuously from the space 20 through the pipe 19 to the interior of the crank case 17, so that the bellows 11 may expand through the cessation of the 95 oil pressure applied thereto.

The construction of the bellows 11 is such that it permits the rod 8 to have a universal motion so that shocks, misplacements, etc. do not effect the advancing, or retarding, of 100 the bellows 11. At the same time, an adjustment is provided by having the rod 6 screw-threaded into rod 8 thereby allowing any initial and final position of the lever 3 to be had. A similar effect on the bellows 11 is 105 caused by the operation of the oil pump suction through the pipe 18, in which case an expansion of the bellows 11 will be caused for obtaining the same effect, but when suction is applied through the pipe 18, it will 110 be desirable to close off 19 entirely and provide suitable bell crank motion in between

the rod 6 and lever 3, for advancing or retarding the timer 1.

The diaphragm 11 is formed as a bellows and being made of metal the same acts as a spring to be compressed by the oil pressure and returns to a normal position on the cessation of the pressure.

It is to be noted that when the engine is cold, the viscosity of the oil will be at a maximum, therefore pressure will build up in the space 20 to a maximum for all speeds. Thus, immediately after starting, or idling speeds, a good advance of the timer 1 is attained, which is desirable because the explosion time in the engine cylinder is protracted at low temperatures. Thereafter, as the engine warms up and the viscosity of the oil lowers, the oil pressure at the same speed will be lowered to normal and the position of the timer 1 will be automatically adjusted for the explosion time of a hot mixture of fuel and air to be fired.

My preferred application of the invention embodies the use of the oil pressure developed by the engine lubrication pump, but the suction developed by said pump is also effective for the purpose described. In each case a pressure generated from the oil pump is the source of power used for actuating my apparatus, in one case positive pressure is employed and in the other case a negative pressure is employed, but as already stated I prefer the application of a positive pressure, which is caused by the oil pump sucking oil from a sump on the interior of the crank-case 17 and circulating the same under pressure through the casing 18.

I claim:

1. In a timer control mechanism, the com-

bination of a casing, a bellows within said casing, the interior of said bellows being open to the atmosphere, an adjustable rod secured to the bottom of said bellows and having its free end provided with means for directly connecting said rod to said lever, a pipe for delivering lubricating oil to the space between said bellows and the walls of said casing, and a pipe for removing the oil from said casing.

2. In a timer control mechanism, the combination of a casing having an opening therein, a compressible, resilient bellows having substantial depth in said casing, one end of the said bellows being closed and the other end open to the atmosphere and secured around the edge of said opening, and an attaching member connected to the closed end of said bellows and extending outwardly through said opening and adapted to be connected to a timer.

3. A timing control mechanism for internal combustion engines comprising a fluid-tight casing having an opening therein, a compressible, resilient bellows member in said casing, a rigid member connected to said bellows and extending outwardly through said opening and adapted to be connected directly to a timer lever, a conduit for conducting lubricating oil to said casing for compressing said bellows for operating said lever for advancing the spark, and a conduit for conducting said fluid from said casing.

Signed at Wilmington, in the county of Los Angeles and State of California, this 16th day of November, A. D. 1923.

CHARLES LAWRENCE STOKES.

CERTIFICATE OF CORRECTION.

Patent No. 1,705,316.

Granted March 12, 1929, to

CHARLES LAWRENCE STOKES.

It is hereby certified that error appears in the printed specification of the above numbered patent requiring correction as follows: Page 2, line 45, claim 1, before the word "lever" insert the word "timer"; and that the said Letters Patent should be read with this correction therein that the same may conform to the record of the case in the Patent Office.

Signed and sealed this 23rd day of April, A. D. 1929.
